OF MAINE.

RING SPINNING OR TWISTING APPARATUS.

No. 820,659.

Specification of Letters Patent.

Patented May 15, 1906.

Application filed September 11, 1905. Serial No. 277,816.

To all whom it may concern:

Be it known that I, CLARENCE E. METCALF, a citizen of the United States, and a resident of Hopedale, county of Worcester, State of Massachusetts, have invented an Improvement in Ring Spinning or Twisting Apparatus, of which the following description, in connection with the accompanying drawings, is a specification, like characters on the drawings representing like parts.

This invention has for its object the production of novel spinning or twisting apparatus of the so-called "rotary-ring" type, whereby the motion of the ring and its control when running at speed is made more uniform and smoother.

My invention also comprehends means for securing the ring-casing to the ring-rail in such a manner that no distortion or deviation thereof can take place.

The various novel features of my invention will be fully described in the subjoined specification and particularly pointed out in the following claims.

Figure 1 is a view in front elevation of spinning or twisting apparatus embodying my invention, the ring-rail and the holder for the casing being shown in section. Fig. 2 is a diametrical section of the rotary ring and casing, showing the construction of the parts not visible in Fig. 1; and Fig. 3 is a top plan view of the holder detached.

I have herein shown the ring 1 of the double-flanged type, having its upper flange 2 forming a raceway for the traveler 3, Figs. 1 and 2, and its lower flange 4 is herein shown as adapted to fit tightly in a socket 5 in the ring-carrier. The latter is thus detachable from the ring; but so far as my invention is concerned the ring and carrier may be made integral, if desired, and such construction I consider fully within the scope of my invention.

Referring more particularly to Fig. 2, the ring-carrier comprises an annular externally beveled or inverted frusto-conical bearing 6, having depending from its lower smaller end a thin sleeve 7. Into this sleeve a metallic collar 8, having at its lower end an external lateral flange 9, is adapted to be forced in assembling the parts, so that the sleeve or collar rotates as a single piece with the ring 1,

the flange forming a downhold device, as will be described. The casing for the ring is an annular member 10, having an internal circular socket 11 at its upper end to tightly receive a non-metallic seat 12 for the bearing, said seat being preferably made of wood impregnated with wax or grease to reduce the friction to a minimum.

The seat is preferably made transversely convex, as shown in Fig. 2, to contact tangentially with the bearing and is concentric thereto, the lifting or axial movement of the ring raising the bearing more or less from the seat and permitting some radial or slow slight lifting movement of the ring to adapt itself to the pull of the yarn when in operation. Below the seat the casing is made conical internally, as at 13, and within the space between such conical face and the outer surface of the sleeve 7 I interpose a lower member or ring 14, preferably of wood treated as is the seat to reduce friction. Said ring 14 rests upon the flange 9, as clearly shown in Fig. 2, and its outer wall is beveled or coned at 15 to correspond to the interior of the casing, the ring 14 being inserted in the casing, and then the collar 8 is forced into position within the sleeve 7 when the parts are assembled. The loose member or ring 14 cooperates with the flange 9 to limit upward axial movement of the rotary ring 1 and the parts movable therewith, the upward movement of the member 14 being limited by the casing. As the member 14 is loosely confined within the casing, it can rotate with the ring 1, and it also has some radial movement, as shown in Fig. 2, the clearances therein being somewhat exaggerated to more clearly show the structure. This loose annular member 14 serves to balance the rotary ring and to give it a smoother and more uniform motion when running at speed, and it also serves as a cushion for radial movements of the ring.

Referring to Figs. 1 and 2, the casing is provided at its top with an external flange 16, which rests on the top of the ring-rail R, Fig. 1, the body of the casing passing through the hole R^x in the rail, and the periphery of the flange is beveled at 17. I retain the casing securely in position by a holder, (shown separately in Fig. 3,) consisting of a flat plate 18, having a circular opening 19, beveled at 20,

to fit the peripheral bevel of the flange 16, the holder being secured to the ring-rail by suitable screws 21, Fig. 1.

By the construction shown a continuous annular retaining engagement is effected between the holder and the casing, this being an important feature of my invention, as thereby there is no chance of distorting or varying the true circular structure of the casing. If such distortion takes place, even to a very slight degree, the smooth and uniform running of the ring is interfered with, and its effectiveness is correspondingly diminished.

My invention is not restricted to the precise construction and arrangement herein shown and described, as the same may be modified or varied by those skilled in the art without departing from the spirit and scope of this invention.

Having fully described my invention, what I claim as new, and desire to secure by Letters Patent, is—

1. The combination, with a rotary ring having a beveled bearing, of a fixed casing having a seat for said bearing, and means to limit upward axial movement of the ring, comprising a loose member confined within the casing below the seat, and a coöperating member rotatable with the ring.

2. The combination, with a rotary ring having a beveled bearing, of a fixed casing having a non-metallic seat for said bearing, and means to limit upward axial movement of the ring, comprising a loose member confined within the casing below the seat, and a coöperating member rotatable with the ring.

3. The combination, with a rotary ring having a beveled bearing, of a fixed casing having a non-metallic, transversely convex seat for said bearing, and means to limit upward axial movement of the ring, comprising a loose member confined within the casing below the seat, and a coöperating member rotatable with the ring.

4. The combination, with a rotary ring having a beveled bearing, of a fixed casing having a seat for said bearing, and means to limit upward axial movement of the ring, comprising a loose non-metallic member confined within the casing below the seat, and a coöperating metallic member rotatable with the ring.

5. The combination, with a rotary ring having a beveled bearing, of a fixed casing having a seat for said bearing, and means to limit upward axial movement of the ring, comprising a loose wooden ring confined within the casing below the seat, and a coöperating annular member depending from the bearing and having an outturned lip to project beneath said wooden ring.

6. The combination, with a rotary spin-

ning-ring having an attached inverted frustoconical bearing provided with a depending cylindrical sleeve, of a fixed casing having an annular seat for and concentric with the bearing, a loose non-metallic ring confined within the casing below the seat, and a collar adapted to fit tightly within the sleeve and having a flange on its lower end to extend beneath the said loose ring, the flange vertically supporting the latter and by its coöperation therewith limiting lifting movement of the spinning-ring.

7. The combination, with a rotary ring having an attached beveled bearing, and a downhold device depending from the latter, of a fixed casing having an annular seat for and concentric with the bearing, said casing being internally conical below the seat, and a non-metallic ring having a conical outer face interposed loosely between the conical portion of the casing and the downhold device to coöperate therewith and limit upward axial movement of the rotary ring.

8. The combination, with a rotary ring having a traveler-raceway, of a ring-carrier connected with the ring and having an annular, beveled bearing, a downhold device depending from the bearing, a fixed casing having a seat for and concentric with the bearing, and a loose non-metallic ring interposed between the downhold device and the casing and limited by the latter in its axial and radial movement, the said non-metallic ring coöperating with the downhold device to limit the lifting of the ring-carrier.

9. The combination, with a rotary ring, of a fixed casing therefor permitting limited axial and radial movement of the ring and a holder to secure the casing to the ring-rail, the holder having a continuous annular retaining engagement with the casing.

10. The combination, with a rotary ring, of a casing therefor permitting limited axial and radial movement of the ring, said casing having a lateral flange adapted to rest on the ring-rail and beveled at its periphery, and a flat holding-plate having a circular opening beveled to fit the periphery of the flange and form annular retaining engagement therewith.

11. The combination, with a rotary ring, of a bearing, and means to limit upward axial movement of the ring, comprising a loose member revolving with the ring.

In testimony whereof I have signed my name to this specification in the presence of two subscribing witnesses.

CLARENCE E. METCALF.
